LADDER FOOT EXTENSION

Frank Noone, Seattle, Wash.

Application November 28, 1936, Serial No. 113,141

2 Claims. (Cl. 228—61)

This invention relates to a ladder foot extension and the primary object of this invention is to provide adjustable extension means for the lower end portions of the side rails of a ladder 5 to compensate for slope or inclination or other unevenness of the surface on which the lower end portion of the ladder rests when the ladder is in a generally upright position such as it will occupy when in use.

10 In the use of a ladder it frequently happens that the ground or the sidewalk or some other support on which it is necessary to place the foot of the ladder will be uneven or will be inclined in such a manner as to make it impossible to place 15 the bottom ends of both side rails of the ladder squarely on such uneven or inclined support. When a ladder is placed on such an uneven or inclined support it will often rest entirely on the bottom end portion of one side rail with the bottom end portion of the other side rail elevated above the support. In such a position the ladder is not firmly and safely supported but is unstable and liable to tip to one side. If blocking is placed under the bottom end portion of the elevated 20 side rail the blocking is liable to slide or roll and the ladder is liable to be unsafe and accidents are liable to result. Also when a ladder is supported entirely or principally on one side rail the presence of a load on the ladder subjects the ladder to a twisting strain which is damaging to the 25 ladder.

It is an object of this invention to provide readily adjustable extension members at the lower end portions of the side rails of a ladder to serve as feet for engaging the surface on which the ladder rests, said extension members extending beyond the bottom ends of the side rails and being adjustable longitudinally of the side rails whereby they may be positioned to rest squarely and evenly 30 on an uneven or inclined supporting surface.

Another object of this invention is to provide a ladder foot extension having a base portion pivotally connected therewith and adapted to automatically adjust itself to conform to the surface on which it is placed.

45 Other objects of the invention are to provide ladder foot extension devices of strong and simple construction which are easily applied to an ordinary ladder and which are reliable and efficient in operation.

50 Other and more specific objects of the invention will be apparent from the following description taken in connection with the accompanying drawing.

55 In the drawing Figure 1 is a front elevation

of the lower end portion of a ladder having these ladder foot extensions applied thereto, showing the ladder foot extensions resting on a sloping support, the upper end portion of the ladder being broken away.

Fig. 2 is a side elevation on a larger scale than Fig. 1, of one of the ladder foot extension devices.

Fig. 3 is a vertical sectional view substantially on broken line 3—3 of Fig. 2, the two plates of the ladder foot extension member being shown 10 spaced apart enough to clear the teeth thereof.

Fig. 4 is a fragmentary sectional view, substantially on broken line 4—4 of Fig. 3, of the base portion of the ladder foot extension device.

Fig. 5 is a fragmentary view in elevation of a 15 ladder foot extension member having a modified form of base member.

Fig. 6 is a fragmentary sectional view showing a cam and lever means for clamping two plate members together.

Fig. 7 is an elevation of the devices shown in Fig. 6.

Like reference numerals designate like parts throughout the several views.

Referring to the drawing, 10 and 11 designate 25 the side rails of an ordinary ladder of conventional form and 12 designates the usual rungs of the same.

A ladder foot extension device is shown operatively connected with each of the side rails 10 and 11 in Fig. 1. Each ladder foot extension device comprises an inner plate member 13 secured by bolts 14 to the adjacent side rail of the ladder and an outer plate member 15 cooperating with said inner plate member. The inner plate member 13 is provided with transversely extending ridges or teeth 16 of V shaped cross section extending across the outer side or face of said inner plate. Said inner plate member 13 is further provided with a bolt member 17 secured thereto near its lower end and projecting outwardly therefrom. The outer plate member 15 is provided with a longitudinally extending slot 18 fitting slidably over the bolt member 17 and is further provided with transversely extending ridges or teeth 19 on its inner side which are adapted to interfit with the teeth 16 of the inner plate member 13. A nut 20, which is preferably a wing nut as shown, is threaded onto the bolt 14 for securely clamping the two plate members 13 and 15 together in any 30 desired adjusted position. The lower end portion of the outer plate member 15 projects below the lower end of the side rail 10 or 11 with which it is connected and preferably has a base member 21 pivotally connected therewith by means of a 35 40 45 50 55 60 65 70 75 80 85 90 95

5 pivot bolt 22. The pivotal movement in both directions of the base member 21 on the outer plate member 15 is limited by engagement of shoulders 23 with the end of the plate member 15 as more clearly shown in Fig. 4. The base member 21 is self-adjusting on the bolt 22 so as to rest more squarely on a supporting surface than it would if it was not pivotally mounted.

10 In Fig. 5 I have shown a fragment of an outer plate member which is similar to the plate member 15 except that it is provided with an integral base member 24 extending at substantially right angles therefrom. The bottom surface of the base member 24 is preferably provided with 15 transverse scores or ridges 25 so that it will be less liable to slide on a surface on which it rests. The bottom surface of the base member 21 is preferably similarly scored as shown in Fig. 4.

15 In Figs. 6 and 7 I have shown a cam means 20 for clamping the two plate members 13 and 15 together. When this cam means is used the clamping bolt 26 which is secured to the inner plate member 13 and passes through a slot in the outer plate member 15 is preferably flattened 25 at its outer end and this flattened portion is positioned between two cam elements 27 which are integral with a cam lever 28. The cam elements 27 are pivoted on a pin 29 which passes through the bolt 26. The pin 29 is off center as respects the cam elements 27 so that when the cam lever 28 is in the position shown in Figs. 6 and 7 the cam elements 27 will bear firmly against the outer plate member 15 and clamp the two plates tightly together. When the cam lever 28 is angularly moved clockwise from the position in 30 which it is shown in Fig. 6 the cam members 27 will be retracted from the plate 15 and sufficient clockwise movement of said cam lever will release the teeth of the two plate members 13 and 15 and permit longitudinal adjustment of the plate 15. This cam and lever means shown in Figs. 6 and 7, when used in place of the wing 35 nut means shown in Figs. 1 to 3, provides a very quick and easy means of clamping and unclamping the two plate members 13 and 15 to permit adjustment of the plate member 15.

40 In the use of these ladder foot extension devices one of said devices is secured to the lower end portion of each side rail of a ladder, as shown in Fig. 1. When the ladder is to be supported on an uneven surface, as the surface 30 shown in Fig. 1, one of the outer plate members 15 will be extended far enough so that it will rest firmly on the supporting surface at a lower position than the other plate member. This provides a firm support for both side rails of the

ladder and obviates any danger of said ladder tending to tip and fall due to inefficient support of one side rail. When the wing nut of the device shown in Figs. 1, 2 and 3 is tightened the teeth 16 and 18 will be held in tightly interfitting 5 relation and there will be no tendency for the two side plates 13 and 15 to move either longitudinally or angularly relative to each other.

10 The foregoing description and accompanying drawing clearly disclose what I now regard as a preferred embodiment of my invention but it will be understood that this disclosure is merely 15 illustrative and that such changes in the device may be made as are fairly within the scope and spirit of the following claims.

15 I claim:

1. The combination with the stiles of a ladder, of a foot for each stile having a base portion to engage the ground, a bolt pivotally mounting each foot on the respective stile to have a swing- 20 ing movement in opposite directions across the end of the stile, said bolt being disposed approximately midway of the length of said base portion and midway of the width of said stile, said end of each stile having a flat surface and said base portion of the foot having an inclined surface 25 closely adjacent and at one side of the axial plane of the bolt that is perpendicular to the plane of said base portion to engage said flat surface on the stile upon movement of said base portion across the end of the stile in one direction, whereby to limit relative movement of said stiles and said base portions in said direction and ensure a stable support of the ladder by said feet.

30 2. The combination with the stiles of a ladder, of a foot for each stile having a base portion to engage the ground, a bolt pivotally mounting each foot on the respective stile to have a swing- 35 ing movement in opposite directions across the end of the stile, said bolt being disposed approximately midway of the length of said base portion and midway of the width of said stile, said end of each stile having a flat surface and said base portion of the foot having oppositely inclined 40 surfaces disposed closely adjacent and at opposite sides of the axial plane of the bolt that is perpendicular to the plane of said base portion to engage said flat surface on said stile upon relative swinging of the stile and the corresponding base portion in opposite directions respectively, 45 whereby to limit relative movement of said stiles and said base portions in said directions and ensure a stable support for the ladder by said feet.

45 FRANK NOONE.
